New Jersey

Application May 5, 1958, Serial No. 50,772

Term of patent 14 years

(Cl. D48—24)

FIG. 1

Fig. 1 is a perspective view of a lantern showing our new design; with the light member pivoted slightly from the vertical;

Fig. 2 is a front elevational view thereof;

Fig. 3 is a side elevational view thereof; and

Fig. 4 is a top plan view thereof.

The base is fragmentarily shown in Figs. 2 and 3 and the handle is omitted in part in Fig. 4 for convenience of illustration.

The dominant features of our design reside in the portions shown in full lines.

We claim:

The ornamental design for a lantern, as shown and described.
